CARBONATING MACHINE

Peter Frank Haythornthwaite, 3A Dallinghoe Crescent,
Milford, Auckland, New Zealand

Filed June 27, 1974, Ser. No. 483,779

Term of patent 14 years

Int. Cl. D15—08

U.S. Cl. D94—3 R

FIG. 1

FIG. 2

FIG. 4

FIG. 5

FIG. 3

FIG. 6

FIG. 7

FIG. 1 is a front top perspective view of a carbonating machine showing my new design;

FIG. 2 is a side elevational view thereof;

FIG. 3 is a side elevational view thereof showing the side opposite that shown in FIG. 2;

FIG. 4 is a bottom plan view thereof;

FIG. 5 is a top plan view thereof;

FIG. 6 is a front elevational view thereof; and

FIG. 7 is a rear elevational view thereof.

I claim:

The ornamental design for a carbonating machine, as shown and described.
